Primary Examiner — Sandra Snapp(74) *Attorney, Agent, or Firm* — Emch, Schaffer, Schaub & Porcello Co., L.P.A.(57) **CLAIM**

The ornamental design for a table, as shown and described.

DESCRIPTION

FIG. 1 is a front elevational view of a table showing the new design, the rear elevation view is a mirror image of the front elevation view;

FIG. 2 is a top plan view thereof;

FIG. 3 is a bottom plan view thereof;

FIG. 4 is a right side elevation view thereof; and,

FIG. 5 is a left side elevation view thereof.

The broken lines shown in the drawings are for illustrative purposes only and form no part of the claimed design.
